DESIGN FOR AN ELECTRIC DISPLAY FIXTURE

Edwin Maxwell, New York, and Jack Kaplan,
Brooklyn, N. Y.

Application October 6, 1934, Serial No. 53,506

Term of patent 3½ years

To all whom it may concern:

Be it known that we, Edwin Maxwell and Jack Kaplan, both citizens of the United States, residing at New York city and Brooklyn, New York, in the counties of New York and Kings, respectively, and both in the State of New York, have invented a new, original, and ornamental Design for an Electric Display Fixture, of which the following is a specification, reference being had to the accompanying drawing, forming a part thereof.

Figure 1 is a perspective front view of an electric display fixture, showing our new design.

Figure 2 is a side elevational view of the same.
We claim:

The ornamental design for an electric display fixture, as shown.

EDWIN MAXWELL.
JACK KAPLAN.
